UNITED STATES PATENT OFFICE.

GUSTAF F. KINDE, OF MONTREAL, QUEBEC, CANADA.

BOLT MECHANISM FOR LOCKING RANGES OF CELLS.

SPECIFICATION forming part of Letters Patent No. 224,546, dated February 17, 1880.

Application filed September 6, 1879.

To all whom it may concern:

Be it known that I, GUSTAF FRANÇOIS KINDE, of the city of Montreal, in the district of Montreal and Province of Quebec, Canada, have 5 invented certain new and useful mechanism for locking and unlocking simultaneously or independently the doors of a range of cells or chambers; and I do hereby declare that the following is a full, clear, and exact description 10 of the same.

My invention, which will be found of use in all cases where a number of boxes, compartments, or chambers are ranged side by side, is, however, specially designed with reference 15 to the ranges of cells in the corridors of prisons or lunatic asylums, or dens in menageries, as it enables the warder or keeper to open any one cell without affording egress from the others by the same mechanism by which all 20 the cells can at will be simultaneously locked and unlocked, the means for operating such mechanism being outside the corridor on which the cells face, or at one end of it.

My invention may be described as consisting 25 in the arrangement, preferably above the cell-doors, of two bars sliding independently in proper bearers, and holding between them the ends of the vertical bars or rods, one to each cell, by which the bolts or latches securing 30 the doors are held in place. In these independently-sliding bars are formed notches or openings, which, when brought together over any one or all of the vertical bars, release it or them from the hold and allow the door 35 to open by a spring or any other usual device. On the end of each of these sliding bars is formed or secured a half-round bar on which a half-spiral thread is cut, the two forming a full screw, and each half being operated inde- 40 pendently by a wheel or disk, the rotation of which will thus give to the bars the independent lateral movement required, each wheel controlling or operating one bar only.

For full comprehension, however, of my in- 45 vention, reference must be had to the annexed drawings, in which similar letters indicate like parts, and where—

Figure 1 is a view of part of a range of cells to which my invention is applied, showing one 50 open. Fig. 2 is an end view, showing operating-disks, &c. Fig. 3 is a part view of sliding

bar with half-round screwed end. Fig. 4 is a section of bracket and bars. Fig. 5 is a sectional elevation of bars, showing head of vertical rod. Fig. 6 is a sectional elevation of 55 bars and vertical rod, showing modification of construction. Fig. 7 is a view of end of screw. Fig. 8 is a sectional top view of screw, eccentric cylinder, and disks. Fig. 9 is a section on line x x , Fig. 8. Fig. 10 is a sectional 60 elevation, showing side view of screw.

A and B are the sliding bars, which form the principal feature of my invention, these being carried in suitable brackets C, secured, by preference, in the intervals between the 65 cells and above the doors, and being, if desired, provided with rollers to facilitate the passage of the bars A, B, which may be in section either of the forms shown in Figs. 4 and 5 or any other which will allow them to pass freely 70 either side of the necks of the vertical bars D, D', and D'', and at the same time hold the several heads d, d', and d'' firmly in place, preventing them from being moved in either direction vertically, preferably by collars or 75 shoulders formed on them, and thus securing the cell-doors, as these vertical bolts or bars require to be lifted in order to release the bolt, lever, or other suitable device fastening the cell-doors E, E', E'', &c., which may be of any ordinary construction, and are usually numbered. To release any one of these bolts, or all at once, the bars A and B are slid along independently, by means to be hereinafter described, until the notches or openings formed 80 in both the bars for the purpose coincide over the special rod (in the drawings shown as D') which is to be released, the warder or keeper, to effect this, only having to bring the pointers A' B' together, as shown, over the mark in the 85 gage F (arranged at the end of the corridor) corresponding with that on the cell-door to be opened.

The notches or openings formed in the bar A are respectively, as shown, lettered a a, a' 95 a', and a'' a'', and are arranged in pairs, those in the bar B being similar.

It will, of course, be impossible to give the exact distance apart and arrangement of these notches or openings, as they must be laid out 100 to suit the building in which they are put up, and vary according to the distance from center

to center of the cells, and the length of the gage, irrespectively of the number of places into which it is divided, having to conform to the space between the first cell and the end of 5 the corridor; but I may say that the distance between the paired notches, such as *a a*, increases in a constant ratio the farther they are from the operating mechanism, which is now to be described.

10 Upon the end of each of the bars A and B is preferably secured, as shown in Figs. 3 and 7, a half-round bar, (marked, respectively, G and H,) upon which is cut a half-box screw-thread, so formed that when the two halves 15 are brought together they make one perfect screw. Upon this double screw, and secured to the wall by a bracket, I, is arranged a double eccentric cylinder, K, constructed as shown more particularly in Figs. 8, 9, and 10, and arranged to cover up alternately each one of the 20 semi-screws G and H, which move freely through it. *k k k* being collars or shoulders formed on it, so as to hold in place and give a fulcrum to the disks L M, the disk L working 25 the screw G, which is threaded into it, and the disk M the screw H, similarly threaded, the rotation of these disks L M thus imparting to the bars A and B, respectively, independent motion. These disks or wheels may be made 30 in any way found most suitable for working them, and, if desired, have inserted in them bushings threaded to suit the semi-screws.

When, by the adjustment of the bars, all the 35 cells in the range have been closed, they may be still further secured by means of a lock arranged as shown at N in Fig. 2, the bolt of which passes through the inner semi-screwed bar and into the outer one. The key of this 40 lock will be the only one required in the building.

The operation of my invention will be so clearly understood from the drawings and the foregoing that it will be unnecessary to make any further allusion to it. I would, however, 45 remark that this arrangement of the independently-sliding bars keeps the cells securely fast-

ened, even while they are being moved by the warder, as until the pointers are brought together at the desired spot and the notches in the two bars coincide at any given point the 50 heads of the vertical bars are kept firmly in place.

It must also be clearly understood that I do not confine myself to any specific means for securing the doors of these cells or dens, all 55 that is required being that the device used shall necessitate the movement up or down of the vertical rod described, and the precise construction of these vertical rods may be varied to suit differing requirements—as, for instance, 60 when the cell-doors are sunk in the wall.

Any number of cells in a range may be fitted with the herein-described invention.

Other mechanism, such as racks and pinions, levers, &c., may be used to give the sliding 65 bars their independent movement, although the device described will be found very effective for the purpose, and is applicable not only in the present instance, but in all cases where independent adjustment is required. 70

Having thus described my invention, what I claim is as follows:

1. The bars A B, moved independently of each other, and operating to lock and unlock either any single cell in a range or all simultaneously, in combination with the vertical bars, the heads of which are held by the sliding bars, substantially as herein set forth. 75

2. The combination, to produce independent reciprocating motion, of two half-round bars 80 having spiral screw-thread worked on same, and a double eccentric cylinder, through which said half-round bars pass freely, said cylinder being cut away alternately on either side, so as to expose each bar, respectively, to the action 85 of a disk or wheel threaded thereon, all substantially as herein set forth.

G. F. KINDT.
